UNITED STATES PATENT OFFICE.

WILLIAM HARLEV, JR., OF OAK PARK, ILLINOIS.

SASH-LOCK.

1,390,436.

Specification of Letters Patent. Patented Sept. 13, 1921.

Application filed March 30, 1918. Serial No. 225,782.

To all whom it may concern:

Be it known that I, WILLIAM HARLEV, Jr., a citizen of the United States, residing at Oak Park, in the county of Cook and State 5 of Illinois, have invented certain new and useful Improvements in Sash-Locks, of which the following is a specification.

This invention relates to a window catch which is provided with means for preventing 10 the reverse rotation of the latching part so that it cannot be released by the insertion of a flat implement between the window sashes. It is therefore a safety catch, and it has a variable engaging member which 15 can be moved toward or from the fixed catch member to vary the distance between the parts so that a more firm locking engagement may be obtained. Other objects will appear hereinafter. The invention consists in the 20 novel construction, combination, and arrangement of the parts.

In the accompanying drawing,

Figure 1 is an elevation of a sash lock constructed in accordance with the principles of this invention, in locked position;

Fig. 2 is a plan view of the same;

Fig. 3 is a section taken on the line 3—3 of Fig. 1; and

Fig. 4 is a perspective of a fastening plate 30 which may be applied to the catches commonly in use.

It is very often an easy matter to unlatch the window sash locks commonly used, from the outside of the window by inserting a thin 35 or pointed instrument between the sashes and moving the rotatable member until it is free from the catch. The present invention provides a ratchet lock that must be positively disengaged before the latch can 40 be reversely rotated.

In this invention, an upper window sash 1 has a catch 2 applied to the lower rail thereof by fastening screws 3 in the well known manner, with an overhanging engag- 45 ing pointed projection 4, and with a prefer- ably integral extension 5 which extends downwardly along the face of the sash to which it is attached by fastening screws 6 at right angles to those inserted from the 50 top, thus greatly strengthening the attachment of the catch, so that it can not be easily pried loose.

Instead of having an integral extension 5, a separate plate 7, as shown by Fig. 4, may 55 be applied over the top of the ordinary

catches of this kind by inserting the screws 3 through screw holes 8 and the screws 6 through holes 9. With either form, a recess 10 is usually formed in the face of the sash so that the outer side of the extension 5 or 60 the plate 7 will be flush with the surface, thus preventing the insertion of an instrument for prying it loose.

Attached to a lower window sash 11 by means of screws 12, is a latch comprising 65 a supporting base 13 having a slot 14 extending toward the catch 2, and a rotatable latching member 15 having an upstanding curved edge 16 for engaging under the projection 4, and an ear 17 forming a finger gripping 70 portion for rotating it. Between the member 15 and the base 13 is inserted a plate 18 having an upstanding toothed edge 19 and a downturned tongue 20 with a slot 21 opening from the lower edge thereof. The mem- 75 ber 15 and this plate 18 are pivotally connected by means of a rivet 22 which has an enlarged portion 23 slidable in the slot 14 and they are both attached to the base 13 by means of a washer 24 larger in diameter 80 than the portion 23 which is attached to the inner end of the rivet 22.

It is therefore obvious that the latching member 15 is movable toward and from the catch 2 because of the slot 14, and in order 85 to adjust and hold the member 15 with respect thereto, the side of the supporting base 13 opposite the catch 2 is provided with a threaded opening 25 in which is an adjust- ing screw 26 having a knurled head 27 and 90 an adjacent reduced portion 28 by which the slot 21 of the tongue 20 is engaged, so that the rotation of the screw 26 causes the move- ment of the plate 18, the member 15, and the connecting rivet 18, in the slot 14, depending 95 upon the direction of rotation of the screw. By this adjustment, a more positive engage- ment is possible, and the inaccuracy of manu- facture and setting are overcome.

Extending from the latching member 15 100 are ears 29 in which a pawl 30 is pivoted that engages by gravity with the upturned teeth of the plate 18, so that as the member 15 is rotated to engage its edge 16 with the pro- jection 4 of the catch, the pawl will engage 105 the teeth successively, preventing the reverse rotation of the member 15 until the pawl is tipped up or manually held out of engage- ment with the teeth.

This construction is simple, durable, and 110

inexpensive in construction, and is practically burglar proof. The adjustability makes it easy to take up shrinkage or wear. It is obvious that others skilled in the art 5 to which this relates may make various changes without departing from the spirit and scope of the invention, and therefore I do not wish to be limited to the particular construction herein shown and described, 10 except as specified in the following claims, in which I claim:

1. In a sash lock, a latch comprising a rotatable member, a supporting base for attachment to the sash, and means for adjust- 15 ably mounting the member in the base.

2. In a sash lock, a latch comprising a rotatable member, a supporting base adapted to be fixed to the sash having a slot in which the member is rotatable, and means 20 for independently adjusting the member in the slot.

3. In a sash lock, a base for attachment to a sash, a latch comprising a rotatable latching member, a toothed plate attached thereto 25 and adjustably mounted on the base, and means in connection with the member for engaging the teeth of the plate and preventing reverse rotation.

4. In a sash lock, a latch comprising a 30 rotatable latching member, a toothed plate to which the latching member is pivotally connected, a base in which the plate is slid- able, said base being adapted to be attached to the sash, means for adjusting the plate

in the base, and a pawl on the member to 35 engage the teeth of the plate.

5. In a sash lock, a latch comprising a rotatable member, a plate to which the member is pivoted, having a depending slotted tongue, a base member in which the member 40 and plate are adjustable, and adjusting means including a screw with a portion engaging the slot of said tongue.

6. In a sash lock, a latch comprising a base member with a slot extending trans- 45 versely thereof, a latching member, a toothed engaging plate therefor, a member for pivot- ally connecting the member and plate, having a portion for slidably mounting them in the slot, and adjusting means threaded into 50 the base member for engaging the plate and moving it and the connected latching member in the slot.

7. The combination with an upper and lower window sash, of a catch affixed to the 55 upper sash, and a latch for the lower sash and comprising a supporting member rigidly attached thereto, a pivoted latching member, means for adjusting the latching member in the supporting member toward and from the 60 catch, and locking means comprising a pawl attached to the latching member, and locking teeth engaged thereby as the latching member is rotated in a direction to engage the catch, preventing the reverse rotation of 65 the latching member until the pawl is manually raised.

WILLIAM HARLEV, JR.
